UNITED STATES PATENT OFFICE.

ELLA G. BREWER, OF BROOKLYN, NEW YORK.

DESIGN FOR A TAPE-MEASURE.

SPECIFICATION forming part of Design No. 27,286, dated July 6, 1897.

Application filed May 28, 1897. Serial No. 638,633. Term of patent 14 years.

To all whom it may concern:

Be it known that I, ELLA G. BREWER, of Brooklyn, in the county of Kings and State of New York, have invented and produced a new and original Design for a Tape-Measure, of which the following is a full, clear, and exact description.

Reference is to be had to the accompanying drawing, which is a plan view of a tape-measure, showing my design.

The leading feature of my design consists of a tape-measure having a longitudinal series of floral decorations on the graduated side. As shown, such floral decorations are arranged in four groups representative of the four seasons of the year. Thus in the yard tape-measure shown there appears from the

first to the ninth inch a series of May-flowers, typical of spring. In the second section, from the tenth inch to the eighteenth, corresponding to summer, forget-me-nots are represented. The third division, from the nineteenth inch to the twenty-seventh, is decorated with a representation of goldenrods, indicating autumn, and in the end portion winter is typified by holly.

I claim—

The design for a tape-measure, as herein shown and described.

ELLA G. BREWER.
